UNITED STATES PATENT OFFICE.

WILLIAM J. BECKER, OF DETROIT, AND JOHN F. BECKER, OF LAURIUM, MICHIGAN.

LOCK.

1,364,024.

Specification of Letters Patent. Patented Dec. 28, 1920.

Application filed December 11, 1919. Serial No. 344,037.

To all whom it may concern:

Be it known that we, WILLIAM J. BECKER, a citizen of the United States, residing at Detroit, in the county of Wayne and State 5 of Michigan, and JOHN F. BECKER, a citizen of the United States, residing at Laurium, in the county of Houghton and State of Michigan, have invented certain new and useful Improvements in Locks; and we do 10 declare the following to be a full, clear, and exact description of the invention, such as will enable others skilled in the art to which it appertains to make and use the same.

This invention relates to locks, and more 15 specifically to the class of locks generally known as mortise locks.

One object of the invention is to generally improve upon locks of this character by providing an exceedingly strong, durable 20 and efficient structure that may be very quickly and easily installed in a cylindrical bore or mortise in the edge of a door, and which may be manufactured at a comparatively low cost.

25 A further object is to provide a lock of this character in which a spring that actuates the latch or bolt also exerts a pressure which frictionally holds the pawl or keeper in both its operative and inoperative positions.

Other objects and advantages may become apparent to persons who read the following details of description in connection with the accompanying drawings in 30 which:—

Figure 1 is a view disclosing one half or a section of the casing and the internal mechanism fitted therein.

Fig. 2 is a longitudinal sectional view 40 through the two casing sections, the section being taken along the line 2—2 of Fig. 3.

Fig. 3 is a view partly in elevation and partly in vertical section, the tumbler and locking pawl being shown in their effective 45 positions for locking the bolt against rotation.

Fig. 4 is a transverse vertical section along the line 4—4 of Fig. 2.

Fig. 5 is a transverse vertical section along 50 the line 5—5 of Fig. 2.

Fig. 6 is a transverse vertical section along the line 6—6 of Fig. 2.

Fig. 7 is a perspective view of the locking pawl detached.

55 Fig. 8 is a perspective view of the tum-

bler and the pawl actuating sleeve seated thereon.

Fig. 9 is a perspective view of the pawl actuating sleeve detached.

Referring to the drawings in detail, in which similar reference characters correspond with similar parts throughout the several views, the casing is composed of an upper section 1 and a lower section 2, although it should be understood that this lock is invertible and reversible and that the section 2 may become the upper section while the section 1 becomes the lower section. These sections may be secured together by any appropriate means including a screw 3, and each section is provided with a track or guideway in which a rack or bolt-actuating bar 4 is slidable longitudinally. Each bar 4 is provided with a series of apertures 5 in which the teeth of a spur pinion 6 engage or mesh, and the pinion 6 is formed with a rectangular aperture 7 therethrough for receiving the shank of a knob or handle whereby the pinion 6 is turned, it being shown in Fig. 1 that the pinion 6 is provided with trunnions 8 which are journaled in bearings 9 formed in the upper and lower sections of the casing. The front end of each bar 4 is turned laterally to provide a shoulder or abutment 10 which engages with a similar shoulder or abutment of a bolt 11, the latter including the usual latch projection which extends through the face plate of the lock and engages with an extraneous keeper (not shown). Moreover, 90 the bolt 11 is bifurcated to receive a spring 12, a cavity 13 being provided for retaining one end of the spring in fixed relation with the bolt. The other end of the spring 12 bears against a retaining member which 95 has a guiding pin 15 on one side, this guiding pin extending into the spring 12 and keeping it substantially straight. The other side of the member 14 is concaved and seated against the convexed surface of a pawl or member such as shown in Fig. 7, this member including a rocking shaft 16 and an arm or radial projection 17, the latter being formed with a lug 18 which is adapted to extend into a notch or recess 19 in the upper 100 casing 1. In passing into the recess 19 the lug 18 enters between a pair of shoulders or abutments 20 of one of the bars 4. The pawl is also provided with a shoulder 21 which engages with the bolt 11 when in the 110

position shown in Fig. 3. It will be seen therefore, that when the pawl is in this effective position, it not only prevents the bars 4 from being actuated, but also prevents the bolts 11 from being actuated by extraneous means.

In order that the pawl may be moved into this effective position and held securely therein, a tumbler 22 is provided with trunnions 23 which are journaled in the upper and lower sections of the casing, and a sleeve 24 is rotatably seated on the tumbler and formed with a lateral extension or projection 25 which normally rests under the part 15 17 of the pawl, as shown in Fig. 2. However, upon rotation of the sleeve 24 into the position shown in Fig. 3, the pawl is moved into the effective position shown in Fig. 3 and stands under the pawl to prevent its 20 disengagement from the latch 11 and from between the shoulders of the upper bar 4. It will be seen, therefore, that the strength of the lock does not depend upon the strength of the shaft 16, for the casing at 25 19 adds its strength.

It should be understood that the tumbler 22 should be normally locked and that a key may be inserted in the key-hole 26 for unlocking the tumbler and turning the same 30 when unlocked. The details of construction of the tumbler locking means are well known to the public, and the following brief description thereof will suffice. One or more plungers or catches 27 are spring pressed and 35 normally held by their springs in locking engagement with the tumbler, the latter being provided with apertures which communicate with the key-hole 26 so that the key releases the tumbler from its engagement with the 40 catches 27. When thus released, the tumbler can be turned by turning the key in the well known manner, and the catches 27 slide upon the tumbler during its rotary movement. The sleeve 24 is provided with a slot 45 28 which receives one end of the middle plunger 27 and permits the sleeve to rotate without interfering with the middle plunger or being interfered with by this plunger. It should be understood that the tumbler 50 turns through an entire revolution in order to enable the key to be inserted and withdrawn while in the same position, and that the sleeve 24 rotates through only about 45 degrees, and therefore, the sleeve is provided with lugs or abutments 29, and that the tumbler is provided with lugs or abutments 30. Therefore, after the tumbler has rotated to approximately 45 degrees from the position shown in Figs. 2 and 8, the lugs 55 30 pick up the lugs 29 and effect the rotary movement of the sleeve 24 from the position shown in Fig. 2 to that shown in Fig. 3.

Although we have described these embodiments of our invention very specifically, it is 60 not intended to limit this invention to these

exact details of construction and arrangement, but changes may be made within the scope of the inventive ideas as implied and claimed.

What we claim as our invention is:

1. In a lock, a bolt, a pair of separately movable bars engageable with said bolt and movable longitudinally to retract the bolt, a rotary member engaged with said bars and operatable to move them longitudinally 75 in opposite directions, and means independent of said bolt to directly engage with one of said bars to prevent this bar from being moved longitudinally.

2. In a lock, a bolt, a pair of flat bars each 80 having a series of perforations in one end portion and a shoulder at its other end, a spur pinion having its teeth in mesh with the perforations of said bars and being operatable to move said bars simultaneously in 85 opposite directions, the shoulders of said bars being engageable with said bolt to retract the latter, one of said bars being formed with spaced abutments, and means movable into the space between said abutments to lock said bar against longitudinal movement.

3. In a lock, a bolt, a bar engageable with said bolt and movable longitudinally to retract the bolt and also being movable independently of the bolt, a pawl engageable with the bolt to prevent its retraction and also being engageable with said bar to prevent its longitudinal movement, and means to actuate the pawl and hold it in its engagement with said bar and bolt.

4. In a lock, a bolt, a bar engageable with said bolt and movable longitudinally to retract the bolt, a pawl, a casing in which the bolt and bar are slidable and in which said pawl is pivoted, and means to move said pawl into locking engagement with said bar and into a recess of said casing so that the casing co-acts with the pivot of said pawl to secure the said bar in its inoperative relation.

5. In a lock, a bolt, means to retract the bolt, a pawl movable from its ineffective position to its effective position for preventing the bolt's retraction, a spring to move the bolt outward, means co-acting with said spring to hold said pawl both in its effective and ineffective positions, and means movable from its normal position to move said pawl to its effective position and hold it in said effective position, said bolt being operatable by the retraction of said bolt to return the spring-controlled pawl to its ineffective position when the last said means is restored to its normal position.

6. In a lock, a bolt, means to retract said bolt, a pawl movable to an effective position for preventing retraction of said bolt, a normally locked tumbler provided with a key-hole and adapted to be unlocked by a key in said hole, and a sleeve movably seated on

said tumbler and provided with a projection which is engageable with said pawl to move it to its effective position, said tumbler being provided with an abutment engageable 5 with said sleeve for causing said projection to actuate said pawl.

7. In a lock, a bolt, means to retract the bolt, a pawl movable to an effective position for preventing retraction of the bolt, a tumbler, a key-controlled catch normally in locking engagement with the tumbler and movable out of said engagement by means of a key insertible in the tumbler and effective 10

to turn the tumbler, and a slotted sleeve rotatably seated on said tumbler and having its 15 slot in position to receive the tumbler-engaging end of said catch during rotary movement of the sleeve, said tumbler being engageable with said sleeve to effect its rotary movement, said sleeve being engageable with 20 said pawl to move the latter into its effective position.

In testimony whereof we have hereunto set our hands.

WILLIAM J. BECKER.
JOHN F. BECKER.
